FOAM PACKAGING TRAY FOR FOOD

Donald K. Jewell, Naperville, Ill., assignor to
Restaurant Technology, Inc.

Filed Jan. 29, 1975, Ser. No. 544,872

Term of patent 14 years

Int. Cl. D9—03

FIG. 3 U.S. Cl. D9—219

FIG. 4

FIG. 5

FIG. 6

FIG. 1

FIG. 7

FIG. 1 is a top front perspective view of a foam packaging tray for food showing my new design;

FIG. 2 is a reduced scale perspective view in an open position;

FIG. 3 is a side elevational view, the opposite side being a mirror image thereof;

FIG. 4 is a rear elevational view;

FIG. 5 is a front elevational view;

FIG. 6 is a top plan view; and

FIG. 7 is a bottom plan view thereof.

I claim:

The ornamental design for a foam packaging tray for food, substantially as shown and described.
